UNITED STATES PATENT OFFICE

137,317

DESIGN FOR A BINOCULAR OR THE LIKE

John T. Armbruster, Niagara Falls, and Irwin A. Bosack, Buffalo, N. Y., assignors to Spencer Lens Company, Buffalo, N. Y., a corporation of New York

Application May 1, 1943, Serial No. 110,094

Term of patent 14 years

To all whom it may concern:

Be it known that we, John T. Armbruster and Irwin A. Bosack, citizens of the United States residing at 237 74th Street, Niagara Falls, and 94 Ivanhoe Rd., Buffalo, State of New York, have invented a new, original, and ornamental Design for a Binocular or the like, of which the following is a specification, reference being made to the accompanying drawings, forming a part thereof.

Fig. 1 is a perspective view of a binocular or the like embodying our design;

Fig. 2 is a front end view of the binocular; and Fig. 3 is a side view on an enlarged scale of the eyepiece only.

The essential features of the design reside in the eyepiece shown in full lines.

We claim:

The ornamental design for a binocular or the like, substantially as shown and described.

JOHN T. ARMBRUSTER.
IRWIN A. BOSACK.
